UNITED STATES PATENT OFFICE

WILLIAM WESTPHAL, OF LOS ANGELES, CALIFORNIA

COMBINED DAVENPORT AND BED

Application filed May 10, 1927. Serial No. 190,177.

This invention relates to combined davenports and beds and more particularly to that type known as davenport beds having a small over-all length.

One of the objects of the invention is to provide a davenport of short length constructed and arranged when opened to make a double bed having what is commonly known as a standard size, to-wit: a length of six feet four inches and a width of four feet four inches.

An object is to provide a davenport bed which when folded will provide a davenport seat having a low or standard height of from eighteen inches to twenty-four inches and when unfolded will provide a bed surface having a standard height of approximately twenty-three to twenty-five inches.

An object is to provide a davenport bed in which the back will be securely held in closed position so that the back will not spring forwardly when the davenport is moved to closed position.

Another object is to provide novel means for hinging the seat to the base structure.

Another object is to provide a novel construction for securing the davenport arms to the frame.

A further object is to provide a davenport bed with a steel frame having standard coil springs secured thereto.

Features of invention reside in the parts and combinations of parts more particularly hereinafter set forth.

Other objects, advantages and features of invention may appear from the accompanying drawings, the subjoined detailed description and the appended claims.

The accompanying drawing illustrates the invention in a form I at present deem preferable.

Figure 1 is a front elevation of a davenport bed embodying my invention, the same being shown folded as a davenport.

Fig. 2 is an end view of the device as shown in Fig. 1.

Fig. 3 is an end view of the device with the seat section shown in partially opened position.

Fig. 4 is a fragmentary vertical section on

enlarged scale taken on line $\alpha 4$, Fig. 1. Dotted lines indicate the opened position of the seat member.

Fig. 5 is a fragmentary vertical section of one arm and spring supporting member taken on line $\alpha 5$, Fig. 11.

Fig. 6 is a fragmentary perspective view of one of the bed spring end extension members and quilt retaining members.

Fig. 7 is a transverse vertical section of my invention showing the davenport bed partially opened to bed forming position.

Fig. 8 is a fragmentary vertical section on enlarged scale taken on a plane indicated by line $\alpha 8$, Fig. 11 illustrating the pivotal connection means of the davenport back to the frame.

Fig. 9 is a fragmentary plan view on an enlarged scale of one end of one of the bed springs.

Fig. 10 is a fragmentary cross sectional view of the rear portion of the davenport frame on an enlarged scale, showing back and rear bed spring section in full lines in the act of being unfolded and showing said rear bed spring section in dotted lines unfolded into bed forming position. The member for closing the space between the rear edge of the bed and the rear wall of the davenport frame being shown in full lines in normal closed position and in dotted lines in bed forming position.

Fig. 11 is a side elevation of my invention showing the parts unfolded into bed forming position.

Fig. 12 is a fragmentary front elevation of one end of the front bed section with the bed end extension member in extended position.

Fig. 13 is a vertical sectional view taken on line $\alpha 13$, Fig. 9 showing the spring end extension member in extended position and showing the mattress in dotted lines on the bed spring with the mattress extension member extended and supported by said spring extension member. The quilt retaining member being in unfolded position.

Fig. 14 is a plan view of my invention unfolded into bed forming position with the mattress in place and having a portion

thereof broken away to disclose the spring construction.

Fig. 15 is a view analogous to Fig. 13 but showing the end extension member of the bed spring retracted and showing a fragmental section of the angle steel spring frame and the coil spring supporting wires.

Fig. 16 is a fragmentary perspective view of one of the davenport arms and bed spring frames to which said arm is connected. The upholstering material that usually covers said arm is removed to show the interior construction.

In general my invention includes a main davenport frame 1, a pivotally mounted reversible or interchangeable seat member 2 and a pivotally mounted reversible or interchangeable back member 3.

The davenport frame 1 is of relatively short length and is formed with a rectangular box-shaped base 4 mounted on legs 5 and a box-shaped rear member 6 upstanding from the rear of said base.

The back member 3 comprises a back frame 7 of angle iron, an upholstered back 8 mounted on the front of said frame and a standard bed spring 9 mounted on the rear of said frame, (see Fig. 7), trunnions 10 are respectively mounted in plates 11 secured to the end members of the back frame 7 near the lower sides of said frame, and which trunnions rest and turn in the lower ends of vertical slots 12 formed in the upper edge of vertical channel irons 13 that are secured to the inside of the end members respectively of the davenport base 4, whereby the back member 3 is detachably and pivotally mounted in said base to swing into upright position to form the back of the davenport, or downwardly into horizontal position to form the rear section of a bed surface. External annular flanges 14 are formed on the outer ends of the trunnions 10 and which flanges rest within the channel irons 13 and hold said trunnions in position in said channel irons. The channel irons 13 are formed with side flanges 15 through which screws 16 are inserted into the end members of the base 4 whereby said channel irons are secured to said base. Telescopic U-shaped extension frames 17 are secured at their ends to the rear side of the back frame 7 as at 18 and extend over the ends respectively of the bed spring 9, at a slight upward inclination, said members being of substantially the same width as the bed spring and resting within the rim 19 of the bed spring. Each extension frame is made in three sections, namely a U-shaped section 20 and two tubular sections 21 in which the end arms of the U-shaped section telescopes, the sections 21 being secured at 18 to the back frame 7. Wires 22 extend across the ends respectively of the bed spring 9 and are coiled at their ends around the side

members of the rim 19 of the bed spring at 23 and 24. U or V-shaped wire hooks 25 are coiled at their ends at 26 around the intermediate connecting members 27 of the U-shaped sections 20 of the extension frames 17, so that the hook points 28 of said hooks will engage the wires 22 and limit the outward extension movement of the sections 20. The ends 28 of the hooks are bent slightly upward so that such ends will pass over and engage the rim 19 of the bed spring when the hook points engage the wires 22 (see Figs. 9 and 13), thus effectually holding and bracing the extension frames in extended position. The hooks 25 are positioned to slide between the coil springs of the bed spring when the frame 17 is extended or retracted. U-shaped wire end members 30 are coiled near their ends at 31 around the intermediate members 27 of the sections 20 of the extension frames 17, so that said members 30 may be swung down flat on said frames when retracted for folding the back member 3 as shown in dotted lines in Fig. 9, or swung upright when said frames are extended, the ends of the members 30 being bent and extended at 32 for engaging the side arms of the sections 20 to limit the upright position of said members as shown in Fig. 6, the member 30 forming a head piece or foot piece for the bed and a convenient means enabling the covers of the bed to be tucked in at the ends. To the lower and rear side of the back frame 7 are connected one end of the springs 33, the other end of which springs are connected to brackets 34 respectively secured to the inside of the end members of the davenport base 4, said springs serving to assist in moving the back frame into closed position and to ease the swinging movement of the back member 3 and seat member 2 and prevent the same from dropping into bed forming position. On the rear end of the bed spring 9 is provided a hook 35 for engaging the lower end of an upholstered or padded closing member 36 that is hinged at 37 to the rear wall of the rear member 6 of the davenport frame, so that when the back member 3 is swung down to bed forming position, said closing member will be swung up into horizontal position by said hook 35 and held in such position to close the space between the rear edge of the bed and the rear member 6 of the davenport, as shown in dotted lines in Fig. 10. Said closing member 36 normally occupying a pendant position, but when the back member starts to swing to the unfolded position, the hook 35 mounted on the rear lower portion back member engages behind the lower end of said closing member, and as the back is unfolded, lifts said closing member 36 to the extended position indicated in dotted lines in Fig. 10, wherein it forms a bridge between the back 130

side of the extended back member and the rear member 6. Stops 38 are secured to the inside of the end members of the base 4 for engaging the upper side of the rear end of the back member 3 and maintain the bed spring 9 in horizontal position to form the bed surface when the parts are moved to bed forming position.

The seat member 2 comprises a rectangular angle iron frame 40, arms 41 mounted on the ends of said frame, a double bed spring 42 mounted in said frame, and an upholstered seat portion 43 on which removable seat cushions 43' are received. The frame 40 is hinged 5 at its forward side to the front member of the base 4 by means of hinges 44. Said hinges are of special construction and arrangement each including a relatively long leaf 45 and a relatively short leaf 46. The leaf 45 is 10 secured to the outside of the front member 47 of the davenport base 4 by screws 48 and to the outside of an angle iron 49 by rivets 50, which angle iron 49 is secured by screws 51 to the upper edge of said front member 47, while the leaf 46 is secured to the inside of the front member of the angle iron seat frame 40 by means of rivets 52, so that when the seat member 2 is folded into seating 15 position, the seat frame 40 will rest below the pivot of the hinge within the angle iron 49 with the seat spring member 53 of the spring 42 and the seat portion 43 positioned at the normal low seat elevation of a davenport, (see Fig. 4), and so that when the seat member is unfolded to make a bed the frame 40 will be positioned and rest above the pivot of the hinge with the bed spring member 54 of the spring 42 at such height as to provide a bed surface of standard height. (See 20 Fig. 4, dotted lines.) The spring 42 comprises a plurality of double conical coil springs 55 which diverge upwardly and downwardly from a point 56 intermediate their ends, the upwardly diverging sections 57 of the 25 spring being surrounded by and connected to a rim 58 to form the seat spring member 53, and the downwardly diverging sections 59 of the springs being surrounded by and connected to a rim 60 to form the bed spring member 53. The springs 55 are mounted at their intermediate points 55 on longitudinal wires 61 and transverse wires 62 at the intersections respectively of said wires, the wires 61 and 62 being detachably connected 30 to the seat frame 40 by hooks 63 on the ends of the wires and inserted in apertures 64 in said frame. Upholstery 65 covers the front of base 4, the hinges 44 and the front of the seat member 2. Folding legs 66 are pivoted 35 at 66' to the seat frame 40 and swing down against stops 66'' on the frame 40 to engage the floor and support the forward side of the seat member when unfolded to make a bed surface (see Fig. 11). End extension frames 40 similar to extension frames 17 are mount-

ed on the seat frame 40 to be extended over the ends respectively of the bed spring member 54. A forward extension frame 68 is mounted on the seat frame 40 to be extended over the forward edge of the bed spring member 54, said frame being of the same construction as the frames 17. Each of the arms 41 comprises an arm frame 70 and suitable upholstery 71 extends over the inside, top and outside of the arm, the upholstery containing a padding 72 over the inside of the arm, top of the arm and inner and outer upper edges of the arm, the padding being enlarged over the outer upper edge of the arm to give the same a rolled finish as indicated at 73. The arm frame 70 includes a forward end member 74, rear end member 75, top connecting member 76 connecting the tops of said end members 74 and 75, and lower connecting members 77 and 78, the lower end of the end members being slotted at 79 to form a pair of spaced lower arms 80 and 81, the inner arms 80 of the end members 74 and 75 being connected by the inner connecting member 78 and the outer arms 81 of the end members 77 being connected by the outer connecting member 77. The connecting members 78 of the arm frames rest within and are respectively secured to the end members of the angle seat frame 40 by means of bolts 82 and nuts 83. The lower edges 84 of the arm frame connecting members 77 rest upon the upper edges of the end members of the davenport base 4 when the seat member 2 is folded into davenport forming position, the lower edges 84 of said connecting members being of the same configuration as said upper edges 85 of said base members which upper edges are concaved to accommodate the convex back 8 when the back member is unfolded to make a bed. (See Fig. 11.)

The back member 3 and the seat member 2 are connected by links 86, one end of each link being connected to one end of back frame 7 and the other end of each link being connected to one end of the seat frame 40, whereby the back member 3 and seat member 2 are caused to swing on their fulcrums and fold or unfold in unison.

A mattress 90 used on the bed is formed with thin foldable extensible end members 91 and with a foldable extensible front flap 92.

The operation of my invention is as follows:

When the seat member 2 and back member 3 are folded into the base 4 and rear upright member 6 respectively as shown in Figs. 1 and 2 my invention is in the form of a davenport. When it is desired to convert the davenport into a bed the seat member is swung upwardly and forwardly by grasping the flap 87 and when raised out of the base 4 the back member 3 through the links 86 is swung forwardly and downwardly until the legs 66 secured to the seat

member 2, and which automatically drop down, rest on the floor and support the bed spring member 54 in horizontal position, and until the frame 7 of the back member 3 engages the stops 38 and arrest the back member and bed spring 9 in horizontal position with the surface of the bed spring 9 and bed spring member 54 in horizontal alignment at a height corresponding to the standard height of a bed surface. The end extension frames 17 and 67 may then be drawn out of their guides into extended position and the end members 30 swung into upright position (see Figs. 6, 12 and 13). The extension member 15 68 may then be moved into extended position. The mattress 90 and its front flap 92 are then unfolded so that the mattress properly rests over the bed spring 9, and bed spring member 54 and the mattress front member 92 rests 20 upon the forward extension 68 to form a double bed of standard length transversely of the seat member 2 and back member 3; the mattress end members 11 may then be unfolded over and on to the end extension frames 17 25 and 67 to provide a double bed of standard length lengthwise of the seat member and back member. The seat member 2 is constructed to provide a relatively great vertical space for the reception of the seat supporting 30 springs, and owing to it being so constructed, it is necessary to provide vertical space for housing it when in the folding position, and also to provide room for it when in the extended position. The proper pivotal attachment 35 is provided for said seat member by reason of it being hinged at 44 adjacent to the upper edge of the front face member 47 of the bed, the hinges being connected to the front side of said seat member at a considerable distance from the seat portion thereof, and the 40 foldable legs mounted on the front side of said seat member being adapted to support the latter when extended with its lower side relatively close to the floor.

45 In the event a bed davenport is desired that provides a bed surface of standard length transverse of the seat and back members the end extension frames 17 and 67 may be omitted; and in the event a bed surface of standard length is desired longitudinally of the seat and back members the extension member 68 may be omitted.

I claim:

1. In a folding bed, a folding member including a bed spring, a telescopic extension frame on said folding member to be extended beyond the spring when said member is unfolded to make a bed, and to be retracted when said member is folded, a wire extending across the end of said bed spring and secured thereto, and hooks on said extension frame for engaging said wire for limiting the extension of said extension frame.

2. In a folding bed, a folding member including a bed spring, a telescopic extension

frame on said folding member to be extended beyond the spring when said member is unfolded to make a bed, and to be retracted when said member is folded, a wire extending across the end of said bed spring and secured thereto, and hooks on said extension frame for engaging said wire for limiting the extension of said extension frame, and for engaging the rim of the bed spring for holding the frame in extended position. 70

3. In a davenport bed, a base having curved upper edges, a folding seat member including a seat frame pivotally connected with the base, a seat on said frame, and arms on the ends of said frame, each of said arms including an arm frame comprising a pair of end members, a connecting member connecting the top of said end members, lower connecting members connecting the lower end of said end members, one of said lower connecting members of each arm frame being secured to one end of said seat frame, and the other lower connecting member having a lower edge conforming to the curvature of the respective upper edge of the base and resting on the respective edge of the base when the seat member is in its folded position, and upholstery over the top, inside and outside of said arm frame. 80

4. In a davenport bed, a supporting frame including a substantially vertical rear wall, a folding back member mounted in said frame, a closing member pivotally mounted in said frame, and means on said back member for engaging and holding said closing member in position over the space between the rear edge of the back member and the rear wall of said supporting frame when the back member is unfolded to make a bed. 90

5. In a davenport bed; a supporting frame including a substantially vertical rear wall, a back member mounted in said frame, a closing member pivotally connected at one end to said frame, and means on said back member for engaging and elevating the free end of said closing member and then supporting it in position to form a bridge over the space between the rear edge of the back member and the rear wall of said supporting frame when the back member is unfolded to make a bed. 100

6. In a davenport bed, a supporting frame including a substantially vertical rear wall, a folding back member mounted in said frame, a closing member pivotally mounted in said frame, and a hook on said back member for engaging and holding said closing member in position over the space between the rear edge of the back member and the rear wall of said supporting frame when the back member is unfolded to make a bed. 110

7. In a davenport bed, a base, a seat member; an arm frame comprising a forward end member, a rear end member, a top con- 120

necting member, and a pair of lower connecting members, the lower end of said end members being slotted to form a pair of spaced lower arms, said seat member comprising an angle iron frame which is pivotally secured to the base so that the davenport is thereby adapted to be unfolded to form a bed, said angle iron having an upright side piece when the seat is in closed position, and the side piece being adapted to pass between said spaced lower arms, and means for securing said angle iron to one of said lower connecting members.

In testimony whereof, I have hereunto set my hand at Los Angeles, California, this 4th day of May, 1927.

WILLIAM WESTPHAL.
